[57] CLAIM

The ornamental design for a caddy for art supplies, as shown and described.

DESCRIPTION

FIG. 1 is a top, left, and front perspective view of a caddy for art supplies showing my new design;

FIG. 2 is a top plan view thereof;

FIG. 3 is a left side elevational view thereof;

FIG. 4 is a right side elevational view thereof;

FIG. 5 is a bottom plan view thereof;

FIG. 6 is a front elevational view thereof;

FIG. 7 is a rear elevational view thereof;

FIG. 8 is a perspective view similar to FIG. 1, with the upper lids shown in open position;

FIG. 9 is a perspective view similar to FIG. 8 but showing the top trays pivoted in an open position; and,

FIG. 10 is a top plan view of the position illustrated in FIG. 9.
